DISK MEMORY MODULE FRONT PANEL

Robert Edward Kalvitis and Donald Agnew Robertson,
Fairport, N.Y., assignors to Xerox Corporation, Stamford, Conn.

Filed July 29, 1974, Ser. No. 492,388

Term of patent 14 years

Int. Cl. D14—02

U.S. Cl. D26—5 C

FIG. 1

FIG. 2

FIG. 3

FIG. 4

FIG. 5

FIG. 6

FIG. 1 is a perspective view of a disk memory module front panel showing our new design;

FIG. 2 is a front elevational view thereof;

FIG. 3 is a right side elevational view thereof;

FIG. 4 is a rear elevational view thereof;

FIG. 5 is a left side elevational view thereof; and

FIG. 6 is a top plan view thereof.

We claim:

The ornamental design for a disk memory module front panel, as shown.
